2 SHEETS-SHEET 2.

UNITED STATES PATENT OFFICE.

ANTHONY NEUMAYER, OF BELLEVILLE, ILLINOIS.

COMBINATION WRENCH AND VISE.

1,194,058.

Specification of Letters Patent.

Patented Aug. 8, 1916.

Application filed May 14, 1915. Serial No. 28,178.

To all whom it may concern:

Be it known that I, ANTHONY NEUMAYER, a citizen of the United States, residing at Belleville, in the county of St. Clair and State of Illinois, have invented certain new and useful Improvements in Combination Wrenches and Vises, of which the following is a specification.

This invention relates to combination tools and is more particularly concerned with a wrench so equipped as to render it capable of employment as a vise in addition to its customary functions.

As a principal object, this invention contemplates the provision of a clamping bracket formed with sockets in which the special wrench of this invention is securable, such wrench being provided with jaw attachments fitting it for use as a vise when supported by said bracket.

More specifically, it is an object of this invention to provide a wrench having a stock seatable in the special bracket of this invention, a fixed jaw being formed upon said stock and a shank carrying a movable jaw being receivable in the stock, such shank being controllable from either of its opposite extremities and such jaws being provided with means fitting the wrench for use as different forms of a vise.

A further object of this invention is to provide vise plates and vise jaws which are respectively securable within the fixed and movable jaws of the special wrench comprehended by this invention in order to equip the wrench for use in a variety of manners.

The above and additional objects which will become apparent as this explanatory description proceeds, are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention, as it is reduced to practice, and throughout the several views of which like characters of reference designate similar parts: Figure 1 is a vertical sectional view taken through both the wrench and the supporting bracket of this invention, the former being equipped as a pipe vise, Fig. 2 is a fragmentary view of

the wrench showing its normal use, Fig. 3 is a similar view showing the fitting of the wrench with vise plates for the handling of squared work, Fig. 4 is an edge view of the subject-matter of Fig. 3, Fig. 5 is a view of the wrench detached and fitted with the pipe clamping jaws, Fig. 6 is a sectional view taken at right angles to Fig. 5, Fig. 7 is a sectional view taken on the line 7—7 of Fig. 6, Fig. 8 is a perspective view of one of the pipe clamping jaws, Fig. 9 is a similar view of one of the vise plates, and Fig. 10 is a fragmentary perspective view illustrating the positioning of the wrench within its ordinary socket.

In the embodiment illustrated there is provided a wrench including a stock 10 preferably formed from a durable metal and having the reduced extremity 11, which is squared as is the main body of the stock. The opposite end of the stock 10 is bored to slidably receive the shank 12 which carries the movable jaw 13 adapted to coact in the customary manner with the fixed jaw 14 integrally formed upon the bored end of the stock 10. This shank is also formed with a longitudinal bore which in its case extends entirely therethrough, such bore 15 communicating with the threaded bore 16 formed through the nut 17, this latter being secured to the shank 12 through the medium of removable bolts or screws 18. An extension screw projects through this threaded bore and the communicating bore 15, such screw 19 carrying upon its inner end the knurled nut 20 which is journaled within the customary slot 21 for manual control of movement of the shank 12. Upon its other end the screw 19 is formed with a head 22 which is recessed in the manner indicated by the numeral 23 for the reception of the key member 24, the movement of which may be readily controlled through the medium of the operating hand wheel 25. It will be seen that the nut 20 and the wheel 25 form means whereby the wrench of this invention may have its jaws adjusted handily in any of its embodied uses.

Adapted to support the wrench of this invention as a vise, there is provided the bracket designated 26 as a whole, such bracket being of the arcuate shape illustrated in Fig. 1, having sockets 27 and 28 formed in its opposite extremities and at right angles to each other. A socket 29 similar to the socket 28 and adapted to receive the

reduced stock 11 in the same manner intersects such socket 28 at right angles thereto and thus provides a means for positioning the wrench in a vertical or horizontal position regardless of the vertical or horizontal position of the bracket 26. One face of the recess or slot 27 is formed with the teeth or corrugations 30 in order to grip the surface of any support upon which the bracket of the combination vise is positioned. Threaded through the opposite surface of this slot is a screw 31 carrying upon its upper extremity the head 32 to which may be secured by any suitable means as illustrated, the clamping plate 33, the teeth 34 of which are adapted to engage the opposite surface of the support from that engaged by the teeth 30. The hand wheel 35 similar to the hand wheel 25 is employed for the ready positioning or removal of this bracket upon the support.

While the foregoing discloses the particular construction of the wrench in general and its associated bracket, the means for adapting such wrench to a variety of uses, 25 as provided by this invention, is now to be disclosed. Upon reference to Fig. 5, it will be seen that both the movable jaw 13 and the rigid jaw 14 of the wrench are formed with the arcuate and toothed gripping edges 30 36 which are those most in use in the ordinary employment of the wrench. It is proposed, however, to equip the wrench with removable means facilitating the employment of this tool as a pipe-wrench and as both a 35 pipe-vise and as one of ordinary construction in connection with squared work.

To these ends recesses 37 are formed in the jaws of the wrench and preferably in the staggered relation of Fig. 6 where one of the slots in the jaw 13 centrally opposes the two similar but spaced slots formed in the rigid jaw 14. In each of these slots is accommodated a right angular gripping jaw illustrated in detail in Fig. 8, such jaw 28 including a pair of legs 39 the inner edges of which are toothed as at 40, and bolt means 41 extending through apertures formed through the jaws and registering with the similar apertures 42 at the apex of each jaw 38. These jaws 38 while fitting the wrench for use both as a pipe-wrench or pipe-vise cannot be used advantageously for the handling of squared work. Accordingly, there is provided for this latter use the vise plates 43 as shown in Fig. 9, each plate having a body portion of sufficient width to extend beyond the sides of the jaws 13 and 14, as shown in Fig. 4, the extending portions carrying guide flanges 44 which serve to seat each plate upon its respective jaw. Rearwardly carried by the plate is a small lug or projection 45 which is adapted to enter the accommodating recess 46 formed at the base of each jaw. Forwardly of the jaw and of the plate fixed thereto are provided the

respective and registering threaded apertures 47 and 48 to accommodate the bolts or screws 49 whereby the plates are securely and removably associated with their jaws.

Fig. 10 illustrates a socket 50 of the usual character in which the stock 10, or the reduced portion 11 thereof, may readily be seated and secured through the medium of keys extending through the socket apertures 51 and with the registering stock apertures 52. A similar means is employed to retain the wrench within its bracket 26, key apertures 53 being formed at right angles to each other through the walls of the bracket sockets and being adapted to severally register with the aperture 54 formed longitudinally of the reduced stock 11 in order to accommodate the securing key 55 which removably connects the wrench with the bracket. 70 75 80

From the foregoing detailed description, the operation of the combination wrench and vise of this invention should be readily apparent in all of its embodiments when being used in the normal manner as a monkey-wrench, the tool should be used in the manner of Fig. 2, manipulation of the jaw 13 being secured through the medium of the knurled nut 20. When equipping the tool as a pipe wrench the jaws 38 are inserted into the wrench jaws in the manner clearly indicated by Figs. 5 and 6 while a pipe-vise is similarly secured by placing the wrench thus fitted in one of the sockets 28 or 29 of the bracket 26 and securing it therein by means of the key 55. In this form the hand wheel 25 is preferably employed for adjustment of the jaws 13 and 14. When a vise for the handling of squared work is to be furnished the plates 43 are oppositely positioned upon the respective jaws 13 and 14 in the obvious manner made known by Figs. 3 and 4. It should accordingly be apparent that a wrench such as provided by this invention can readily take the place of four separate tools and is moreover more readily carried about by a mechanic who is limited to few tools than the heavy pipe and angle vises which would otherwise be necessary. While in the foregoing, however, there has thus been illustrated in the drawings and described in the specification such combination and arrangement of elements as constitute the preferred embodiment of this invention, a reduction to practice thereof should be limited only by the appended claims.

What is claimed is:—

1. The combination with a wrench including a stock, having a reduced extremity, a shank slideable in the opposite extremity of said stock, a jaw rigid with said shank, and a jaw rigid with said stock, of a bracket formed with intersecting sockets for the several receptions of said reduced extremity in variously positioning said wrench as a vise. 125
  2. In a wrench, a stock having a longi- 130

- tudinal bore, a shank slidable in said bore, and similarly bored from end to end, a jaw carried by said shank, a jaw carried by said stock, a screw for determining movement of said shank with relation to said stock, and means for operating said screw at each extremity thereof.
3. The combination with a wrench including a stock, a shank slidable in said stock, 10 jaws carried by said stock and shank, a screw member controlling the movement of said shank, a nut carried at one extremity of said screw member for manual control thereof, removable key means operable at the opposite extremity of said screw for a similar control thereof, of a bracket formed with intersecting sockets for the reception of said shank in variously positioning said wrench as a vise, and means for mounting 20 said bracket upon a support.
4. The combination with a wrench having a longitudinally bored stock with an integral laterally projecting jaw on one end and a reduced extension on the other end in alignment with said stock and provided with a transverse perforation, a longitudinally bored shank slidable in said stock with a jaw on one end mating with the jaw on the stock and a short thread terminating the bore at 25 its opposite end, a screw in the bore of the shank passing through the threaded end and engaging therewith, means at each extremity of said screw for operating the same, a support for holding the wrench having a socket 30 in one end for the reduced extension on said stock, and a key fitting transversely in said support and the perforation in the reduced extremity.
5. In combination with a wrench having a longitudinally bored stock opening through one end only, an integral laterally projecting jaw on the open end of said stock and a reduced extension on the other closed end in alignment with said stock and provided with a transverse perforation, a shank slidable in said stock with a jaw on one end mating with the jaw on the stock, said shank having a longitudinal bore extending entirely through the same, a nut removably secured to the end of the shank opposite the end provided with the jaw, a screw in the bore of the shank passing freely therethrough and engaging with said nut, a head on the inner end of said screw for turning the same and moving the shank longitudinally, a socket in the opposite end of said screw to receive means for turning the same, a support for the wrench having a socket therein for the reduced extension on the shank, and a key fitting the transverse perforations in the support and the perforation in the reduced extremity.

In testimony whereof I affix my signature in presence of two witnesses.

ANTHONY NEUMAYER
